MOVABLE SUSPENSION FRAME

Frank E. Madden, Oakland, Calif.

Application April 5, 1938, Serial No. 200,113

4 Claims. (Cl. 105—51)

The present invention relates to movable suspension frames by means of which various types of apparatus can be mounted in such a manner as to be made readily accessible for inspection and repair.

The invention may be embodied in installations covering a wide range of use, and is not to be construed as limited to association with any particular form of apparatus. It will be described 10 herein, for purposes of illustration only, as designed for the suspended mounting of auxiliary apparatus beneath the frame of a railway car, for which use it is especially suitable.

Auxiliary apparatus, such for example as air 15 conditioning ice engines, as used on railway cars, are usually mounted under the frame of the car, but must be suspended in such a manner that they can be drawn out to an accessible position for inspection, servicing, and repair. The side 20 sills of the car extend down below the floor structure, so that when the auxiliary apparatus is mounted low enough to clear the bottom of the side sill, it hangs some distance below the floor. This is objectionable, not only because it restricts 25 the permissible height of the auxiliary apparatus, but also because the relatively long suspension frame permits excessive vibration of the apparatus.

The principal object of the present invention is 30 to provide a suspension frame which permits the suspended apparatus to be moved both vertically and horizontally, so that, in the case of apparatus suspended beneath a railway car for example, it can be lowered to clear the side sill of the car and drawn out beyond the side of the car for 35 servicing, and then moved back under the car and raised to operative position close to the floor structure and above the bottom of the side sill. Another object of the invention is to provide a 40 suspension frame of the described type which is easy to operate and which is strong and rigid enough to hold the suspended apparatus securely in either operating or servicing position.

These and other objects and advantages of the 45 invention will be made more apparent by the following description, which should be read with the understanding that changes, within the scope of the claims hereto appended, may be made in the form, construction and arrangement of the several parts herein shown and described, without departing from the spirit of the invention.

One embodiment of the invention is illustrated in the accompanying drawing, wherein

Fig. 1 is a side elevation, with certain parts in section, of a movable suspension frame, showing

the suspended apparatus in extended or servicing position, the suspension frame being mounted beneath the under-frame of a railway car.

Fig. 2 is a view similar to Fig. 1 showing the suspended apparatus in operative or retracted position.

Fig. 3 is a section taken principally on the line 3—3 of Fig. 1, the suspended apparatus being shown in elevation.

In the drawing, the reference numeral 4 designates a box or housing inclosing an apparatus which is to be movably suspended beneath a railway car. The details of said apparatus form no part of the invention and have been omitted from the drawing. 5 is a portion of the longitudinal 10 center sill of a car, 6 is one of the side sills, 7 is the lower portion of the side sheathing of the car, and 8 is the floor line.

There are two spaced and oppositely arranged 15 suspension frames, one at each side of the suspended housing 4. Said frames are identical in construction, and therefore only one has been shown in the drawing. Each frame comprises a fixed horizontal angle member 9 having its inner 20 end secured to the center sill 5 and extending out to and having its outer end secured beneath the side sill 6. Vertical brackets 10 extend downwardly from the member 9 and support a lower horizontal fixed member 11, whose inner end is 25 secured to the center sill 5.

An inclined rising track member 12, Fig. 1, 30 preferably of channel section, has its inner end pivoted at 13 to the fixed portion of the frame near the center sill 5, and extends outwardly to about the side of the car, its outer end resting upon a lifting screw or jack 14 which is threaded through a nut 15 welded to the lower fixed member 11. A folding track member 16, also preferably of channel section, is hinged at 17 to the front end of the rising track 12, and extends out horizontally therefrom. A diagonal tension brace 18 pivotally connected at 19 with the folding track 16 and secured to the upper frame member 9 by a removable bolt 20, supports said folding track in its extended position shown in Fig. 1.

The apparatus housing 4 has rollers 21 which travel upon the tracks 16 and 12. When said housing is in accessible servicing position, extended beyond the side 7 of the car, the rollers 21 rest upon the folding track 16, as shown in 35 Fig. 1. When it is desired to shift said housing to its concealed position beneath the car, it is pushed inwardly, its rollers traveling up the rising track 12 until the rear roller encounters a 40 fixed stop 22, which limits its inward movement. 45

The rising track 12 is then elevated to horizontal position by means of the jack screw 14. For the sake of safety and rigidity, a spacer block 23, Fig. 2, is inserted between the forward end of said rising track 12 and the lower fixed frame 11, to take the weight off the screw 14. A bolt 24 holds said block in place, and also holds a stop 25 which is placed in front of the forward roller 21. The bolt 20, Fig. 1, at the upper end of the brace 18, is removed and the folding track 16 is swung downwardly and rearwardly to the position shown in Fig. 2, in which position it is held by fastening the free end of the brace 18 to a lug 26.

It will be seen from Fig. 2 that the top of the housing 4 is above the bottom of the side sill 6, this elevated position being achieved partly by the rollers 21 running up the inclined rising track 12, and partly by raising said track to horizontal position by means of the screw 14. The housing 4 is thus suspended under the floor 8 and closer thereto than would be possible if it were permitted to have only horizontal movement. When in extended position, shown in Fig. 1, the housing is almost entirely outside the side line of the car, where its interior apparatus is accessible for servicing.

I claim:

1. Means for movably supporting an object comprising a fixed frame, a track member having one end pivotally connected with said frame, a screw carried by said frame and engaging the other end of said track member to move it from inclined to horizontal position, an extension movably connected with the last mentioned end of said track member and forming therewith a continuous track on which the object is movably supported, said extension being retractable away from its continuous track forming position.

2. Means for movably supporting an object beneath a railroad car, said car having a floor and an underframe with a side sill extending downwardly below said floor, said means comprising a track member having a portion mounted on said underframe for vertical movement beneath the floor of the car, said track member having a second portion movably connected with the first portion for extension beyond and re-

traction within the vertical plane of said side sill, said portions forming a track on which the object is supported for traveling movement from an accessible position outside said side sill to a retracted position inside said side sill with the top of said object above the bottom of said sill.

3. Means for movably supporting an object beneath a railway car, said car having a floor and an underframe with a center sill and a side sill extending downwardly below said floor, said means comprising a bracket secured to said underframe, a track member having its inner end pivotally connected with said bracket, the outer end of said track member being vertically movable, a second track member movably connected with the first track member as an aligned extension thereof, said second track member being movable to a retracted position beneath the car, and said track members when in alignment forming a continuous movable track for supporting the object and upon which it may be moved from an accessible position outside said side sill to a retracted position beneath the floor of the car between said center and side sills.

4. Means for supporting an object beneath a railway car, comprising a frame fixedly mounted beneath the floor of the car, a track member having its inner end pivotally mounted on said frame and its outer end vertically movable, a second track member aligned and pivotally connected with the outer end of the first track member for swinging movement from a substantially horizontal position extending outwardly beyond the side of the car to a retracted position beneath the first track member, said track members forming, when the second track member is extended, a continuous track on which the object is supported for movement from an accessible position outside the side of the car to a retracted position beneath the floor thereof, the vertical movement of the outer end of the first track member causing the retracted object to be elevated to a position in proximity to said floor, and means for supporting said outer end in its elevated position.

FRANK E. MADDEN.
